(57) **CLAIM**

The ornamental design for a pipe for vacuum cleaner, as shown.

DESCRIPTION

FIG. 1 to FIG. 4 are elevational views, each rotated by 90°, of the pipe for vacuum cleaner according to the invention; FIG. 5 is an elevational view of one end of said pipe for vacuum cleaner;

FIG. 6 is an elevational view of the other end of said pipe for vacuum cleaner; and,

FIG. 7 is a perspective view of said pipe for vacuum cleaner.
